UNITED STATES PATENT OFFICE.

EDWARD C. HOFFMAN, OF CLEVELAND, OHIO.

DESIGN FOR A HINGE MEMBER.

SPECIFICATION forming part of Design No. 33,855, dated January 8, 1901.

Application filed December 10, 1900. Serial No. 39,439. Term of patent 7 years.

To all whom it may concern:

Be it known that I, EDWARD C. HOFFMAN, a citizen of the United States, residing at Cleveland, in the county of Cuyahoga and 5 State of Ohio, have invented and produced a new and original Design for a Hinge Member, of which the following is a specification, reference being had to the drawing forming part thereof.

10 The single figure of the drawing is a perspective elevation of my new and original design.

As thus illustrated, the leading or material feature of my design consists, essentially, of 15 a hinge member having the appearance substantially as shown and in which the peculiar shape and arrangement of the lateral projections 1, 2, and 3, respectively, distinguish the design in the art. Projection 1 has an ornamental top finish, and the end of projection 20 2 is smooth and rounded in its outer portion

and is more conspicuous than the others by having somewhat higher elevation from the body 4 of the said member, as well as being wider. Projection 3 resembles projection 1, 25 less its ornamental top, so that the three projections 1, 2, and 3 differ from one another in appearance, and thus emphasize the originality and peculiarity of the design. The top surface of body 4 is decorated with attractive scrollwork, thus giving a finish pleasing to the eye.

What I claim is—

The design for a hinge member, substantially as herein shown and described. 35

Witness my hand to the foregoing specification this 4th day of December, 1900.

EDWARD C. HOFFMAN.

Witnesses:

M. A. SHEEHAN,
R. B. MOSER.
